ENVELOPE

Anthony C. Benedict, Rockville Centre, N. Y.

Application November 15, 1934, Serial No. 753,074

7 Claims. (Cl. 229—72)

This invention relates to improvements in envelopes and the like and has for a main object to provide an end loading envelope compartment which is more easily loaded with mailing matter or the like than end loading envelopes as heretofore provided, with a saving in time required to load or to empty the compartment of its contents.

Other objects of the invention and advantages derived therefrom will in part be obvious and will in part appear hereinafter.

My invention is embodied in an envelope as hereinafter described in which

Figure 1 shows a front view of a duplex envelope having a letter compartment in which the invention appears.

Figure 2 is a view of the under side of the front wall of this letter compartment showing the construction of the compartment.

Figure 3 is a horizontal sectional view of this envelope on line with the top edge of part 3 Figure 1, with some of the dimensions exaggerated.

Figure 4 is a vertical sectional view of part of the same envelope on line with the vertical right edge of part 3.

Figure 5 shows a differently constructed envelope compartment embodying the invention.

Figure 6 shows still a different construction.

Figure 7 is a vertical sectional view of Fig. 6 on line with the right end of the enclosure 11.

Throughout the specifications and the claims the address side of the envelope or compartment will be referred to as the front and the opposite side as the back. The ends or sides of the envelope or compartment may be referred to as the left or right but such references are for convenience in referring to drawings and not used for purposes of limitation.

End loading envelopes or compartments, that is generally oblong envelopes having their entrance for loading with mailing matter and the like at one of their shorter edges so that, for instance, a letter suitably folded to fit is inserted thereinto endwise, have been found less convenient to load or to empty than side loading envelopes having the loading entrance at a long edge. This is mainly for the obvious reason that an end loading entrance does not gap open as readily or as much to receive the mail as a side loading entrance which of course is wider. On the other hand, end loading envelopes or compartments have advantages in other ways, and the present invention removes defects in such envelopes so that they can be loaded and emptied easier and more quickly than in the prior art.

I achieve this result by leaving the front wall of the compartment loose from the back wall at and for a substantial distance away from a side of the enclosure space in the compartment at the loading entrance, and the entrance is made wider than the enclosure space. The parts forming the entrance therefore separate from each other and the entrance gaps open readily and farther than would otherwise be the case. A letter, for instance, suitably folded can therefore be started into the compartment with relative ease, because the walls do not interfere, and having been started, the letter slips easily on into the compartment because the walls being but loosely joined do not grip it and delay the operation.

Looking at Figures 1 to 4, it will be seen that there is a compartment formed at the front of a duplex envelope, which latter is made from a single blank of paper, by part 3 being folded over and gummed to part 2 by the adhesive strip 8. The compartment is closed along its left and along its top edge as far only as A which is located a suitable substantial distance from the bevelled corner C. The bottom edge of the compartment is closed by the fold at the bottom of the envelope, the lower edge of part 2 being held in this fold between the back 1 of the envelope and part 3, thus forming the back of the smaller compartment. The entrance 13 for loading the compartment extends from the end A of the adhesive strip 8 under the top edge of the compartment's front wall 3 and under the corner C and the entire (in this example) right end of 3 to a point B, the front wall for the entire distance A—B being loose from the back wall. There is thus formed between 2 and 3 an enclosure space which is bounded by the bottom fold of the compartment, the inner edge of the adhesive strip 8 along the end and top of the compartment, and a variable line from the right end of the inner edge of strip 8 to the right end of the compartment at the base of the flap 6, thence along this flap base a line to the bottom fold. This enclosure space is adapted for containing a generally oblong enclosure which may be substantially rectangular in shape as illustrated at 11 and position lines 12. Additional space, which is co-extensive with the enclosure space, may exist in the compartment, which is not likely to be occupied by the enclosure. Part 3 between A and B being loose from 2 tends to separate from it forming a gap which facilitates insertion of a letter or the like. This gap is clearly indicated at 13, and of course it may be augmented by suitably scoring or otherwise bending back the loose

corner part of front wall 3 between corner C and the line A—B as should be understood in the art. It should be obvious that corner C being loose an enclosure to be inserted can be started through 5 the entrance 13 under or either side of the corner, and sidewise or endwise or cornerwise of the enclosure. It will be noted that the back wall of the compartment, formed by part 2, extends under the entrance 13 and out therefrom to the 10 right and upward, so that it will serve as a ready guide to facilitate insertion of a letter, for instance, into the entrance and the compartment.

In Figure 1 the letter compartment is seen with a usual address window 9 and a closing flap 6 on 15 part 2 provided with sealing means 7, and at 10 are shown position lines which indicate the approximate position of the flap and sealing means when the compartment is closed as for mailing. It should be noted that sealing means 7 extends 20 along the top edge of flap 6 so as to overlap on to part 2 as well as on to part 3 when the flap is in the closed position and sealed as for mailing, and thereby the two walls of the compartment are held firmly together at or near corner C as well 25 as elsewhere. Thus there may remain an open space under part 3 between A and where flap 6 closes the entrance 13 but this is relatively small so that the contents cannot leave the compartment therethrough, and the compartment may be 30 inaccessibly sealed as required for first class mail. Of course the compartment may be arranged so as to have flap 6 reach to A if desired, but this is not necessary. A may be located at any suitable point and corner C may be bevelled as shown or 35 rounded or fashioned in any suitable manner. It should be understood that the larger compartment between parts 2 and 1 may be formed in any manner and as shown is formed by the folds at the top and the bottom of the envelope and the 40 end closing flap 4 on part 2 is bent over the end of part 1 and secured to the back thereof, while the large flap 5 on part 1 is for closing the larger compartment after loading.

Figure 5 shows a similarly constructed envelope, 45 but in this example the loading entrance 13 of the smaller compartment which extends from A to B under edges of the front wall 3 is arranged to be closed after loading by sealing down the corner C and adjoining edges by means of adhesive strip 7 which may be provided on the under 50 side of part 3 as indicated or on part 2. At 14 is indicated a spot or strip of adhesive which holds part 3 to part 2 and entrance 13 ending at B does not include the open end of the compartment 55 in its entirety. However, a substantial part of the end is open and loading may be said to be done at the end as well as at the side of the compartment, or at the corner.

As explained in connection with Figure 1, the 60 corner C in Figure 5 is also left loose from the back wall 2 of the compartment in manufacture, as are also the adjoining edges of part 3 to A and B, thus forming a relatively wide gapping 65 entrance 13 for loading and through which an enclosure as illustrated at 11 can be easily and quickly inserted, and thereafter this loose part may be stuck down and the entrance closed by the adhesive means 7. Thus there is formed, 70 when the compartment entrance is closed, in the small compartment shown, a substantially rectangular oblong space for holding an oblong enclosure made to fit, this space being bounded at the left by the inner edge of 8, at the top by a 75 line along the inner edges of 8 and 7, at the right

by a line along the inner edge of 7 to the bottom fold, and at the bottom by the fold of the envelope.

Figure 6 presents also an envelope having a larger compartment constructed in a similar manner to that used in Fig. 1, with the smaller 5 compartment illustrating a still different arrangement of its parts and loading entrance. In this example the front wall 3 of the small compartment is not gummed at its left end to part 2 but may have a flap which is bent backward and 10 secured to the back of the envelope or to part 4 in a usual manner, and the enclosure space in this compartment extends to the left end of the envelope. The adhesive strip 8 secures the top edge of the front wall 3 throughout its length to 15 part 2 so the entire top edge of the compartment as well as its left end and bottom edges is closed. The right end of the compartment is made substantially wider than the other end so that an open loading entrance 13 is provided extending 20 from A to B which is substantially wider than a space occupiable by an enclosure of maximum width to fit the oblong space which is formed by the bottom of the compartment at the bottom fold, the left end, the inner edge of adhesive strip 25 8 from the left end to angularity D, and a line approximately parallel to the bottom of the compartment extended from D to the base of flap 6 and a line along said base to the fold at the bottom of the compartment. The flap 6 is on 30 part 2 and will close the compartment entrance when folded against part 3 as indicated by the position lines 10 which indicate not only the approximate closed position of flap 6 but also of the sealing means 7. A strip of adhesive may be 35 provided as shown extending along the top edge of flap 6 toward the flap's base, and as shown this will, when the flap is sealed down, adhere to part 2 as well as to part 3 and, with part 6, will strengthen the compartment at or near A as 40 illustrated. The strip 1a serves a similar purpose and when stuck to part 2 will prevent an enclosure which extends out beyond the compartment's entrance 13, as illustrated by 11, from shifting its position unduly in the direction of A 45 so as to possibly prevent an address on the enclosure from registering properly through the window 9. However, the strip 1a may not be used, as when the horizontal inner edge of adhesive strip 8 is long enough and close enough 50 to the enclosure to hold it properly in position as illustrated in Fig. 1.

At Figure 7, there is indicated at 15 by position lines the way the adhesive strip 1a may hold the walls of the compartment together at the entrance 13.

It appears that in all cases is the mouth, or loading entrance of the letter compartment illustrated relatively wider than the general width of the compartment, also that the front wall of the 60 compartment is loose for a substantial distance at a side of the space intended to be occupied by enclosures adjoining where it intersects the entrance, and as a result of this the entrance tends to spread or gap open more readily than 65 in envelopes of end loading type in which the walls are closely joined at the edge of the enclosure space. In some cases the space intended to be occupied by the letter or other enclosure is less than the total space within the envelope and 70 the extra space is incidental to an enlargement of the compartment at the entrance to provide the easier loading which is an object of the invention.

It should be understood that the constructions 75

shown in the drawings are illustrative only and not used for purposes of limitation, and may be altered or changed or interchanged within the principle of the invention and the scope of the claims. Also that, although a duplex envelope having another compartment formed in combination with the compartment in which the invention appears is shown in the drawings, the invention may be embodied in envelopes and the like of other kinds. However, there appears a particular advantage to be derived from it in duplex envelopes in some cases.

I claim:

1. A duplex envelope having a generally oblong compartment, the latter having an end loading entrance which is substantially wider than the general width of the compartment whereby relatively easy loading is provided, said entrance being without communication with another compartment provided in the envelope and said entrance being arranged to cooperate to provide relatively easy loading of the former compartment with a continuation of the back wall of this compartment which extends in more than one direction outside from the entrance and serves as a guide to steer a suitably folded letter into said entrance.

2. A duplex envelope having a relatively large compartment and a smaller compartment, each having its own individual closing means, said smaller compartment being without access from the larger, the smaller having a loading entrance formed by the front wall thereof being loose from the rear wall along at least the major part of one end and a substantial part of a side edge of the space provided therein for a rectangular enclosure made to fit this compartment, a partition wall between said compartments extending continuously beneath the length of said entrance and continuing outside beyond the entrance a substantial distance in more than one direction therefrom so as to substantially facilitate inserting enclosures into the entrance, the width of the entrance being substantially greater than the general width of the smaller compartment so as to substantially facilitate the loading operation.

3. An envelope compartment having an end loading opening at an end thereof and part of a side adjoining said end being also open for a substantial distance so as to form an entrance that is substantially wider than the compartment,

and an extension of the back wall of said compartment out beyond the entrance in more than one direction forming a guide adapted for readily steering enclosures into said entrance.

4. A duplex envelope compartment generally 5 oblong in shape having a loading entrance, which is substantially wider than the compartment, formed under and extending for a substantial distance either side of a corner of the front wall of the compartment, which latter is loose from the 10 back wall, and an extension of the back wall of the compartment in more than one direction outside from the entrance adapted for readily guiding enclosures into the entrance.

5. A duplex envelope compartment generally 15 oblong in shape having a loading entrance, which is substantially wider than the compartment, formed under and extending for a substantial distance either side of a corner of the front wall of the compartment, which latter is loose from the 20 back wall, said loose corner part being formed to a bent back position causing the entrance to gap open so as to facilitate insertion, and an extension of the back wall of the compartment in more than one direction outside from the entrance 25 adapted for readily guiding enclosures into the entrance.

6. A duplex envelope compartment generally oblong in shape having an end loading entrance at an end of the compartment which is made 30 wider than the general width of the compartment, said entrance being also substantially wider than the general width of the compartment, and the back wall of the compartment having an extension outside beyond the entrance so as to act 35 as a guide for enclosures being inserted thereinto.

7. A duplex envelope compartment generally oblong in shape having an end loading entrance at an end of the compartment which is made wider than the general width of the compartment, said 40 entrance being also substantially wider than the general width of the compartment, and means for holding a rectangular enclosure such as a folded letter in position so that an address on the letter will be kept properly registered through an 45 address window which is provided in the compartment, and the back wall of the compartment having an extension outside beyond the entrance adapted to act as a ready guide for enclosures being inserted thereinto.

ANTHONY C. BENEDICT.
